John H. O'Bara

Attorney

UNITED STATES PATENT OFFICE.

JOSEPH M. HURLEY, OF MINNEAPOLIS, MINNESOTA, ASSIGNOR TO DOUGLAS C. MCCLAIN, OF MINNEAPOLIS, MINNESOTA.

CARD HOLDER.

Application filed October 2, 1926. Serial No. 139,182.

This invention relates to card filing devices and the main object is to provide means of a novel and practical nature for detachably securing data cards to a card holder such as a 5 pocket folder, or card case, of the type which is frequently employed by solicitors and salesmen, although it will be obvious that the card-securing method may also be employed to advantage in filing systems such as are 10 frequently found in modern offices. The style of card employed in the present instance is identical with that shown in my co-pending application, Ser. No. 139,181, filed 15 of even date herewith, and it will thus be seen that the same cards K, as used for office purposes in connection with the filing device shown in the co-pending case, may be interchanged with or substituted for cards used in connection with the folder herein 20 shown, and as used by employees who travel away from the home office.

The device embodying my invention is illustrated in the accompanying drawing, in which:

- 25 Fig. 1 is a perspective view of the device.
Fig. 2 is a plan view of one of the cards employed.

The card holder consists, in the present instance, of a pair of panels or plates A and B 30 which are hingedly connected by a pliable intermediate portion C. The panels may be made of any suitable material, but are preferably made of pliable layers of material, stitched together, as at D and E, so that it 35 will readily conform to the pocket in which it may be carried.

Each panel is provided, at its upper corners, with a pair of diagonally arranged straps F, which are each sufficiently open to 40 permit a number of card corners to be inserted. These straps may be elastic, but should at least be flexible, so that they will not keep the case open any more than the thickness of the cards will require. The straps are 45 secured by having their ends inserted through parallel, horizontal slots G, in the inner layers of the panels, and are then securely fastened between the panel layers by having their ends secured by the stitchings D and E. 50 The cards H to be secured are rectangular in

shape, and at their ends near their upper corners are provided with notches I, thus giving a tongue effect J to the corner portions. The method of attaching the cards in place is almost obvious from the illustration in Fig. 55 1. After one corner of the card is projected under a strap F the opposite corner may be similarly projected, by first bowing the card upward. The card, or several of them, may be quickly removed in the reverse 60 manner.

It will be noted that as the slots G are parallel with the notches I and upper edges of the cards, the straps will form very snug pockets for the card corners. And as the 65 straps F extend diagonally in from the notches I, it will be seen that they not only secure the tongues J, which are the weakest parts of the cards, but project considerably 70 inward from the notches I and thus bear against the stronger body parts of the card, and reduce any tendency of the card to tear.

It is understood that suitable modifications may be made in the general design and structural details of the invention as herein shown and described, provided, however, that said modifications come within the spirit and scope of the appended claims.

Having now therefore fully shown and described my invention, what I claim to be new 80 and desire to protect by Letters Patent is:

1. A card holder comprising a panel having a row of stitching thereabout, a pair of diagonally disposed straps at two corners of 85 the panel and secured thereto by said stitching.

2. A card case comprising a pair of rectangular panels hingedly secured together, each of said panels comprising two layers of 90 material stitched together, the inner layer of each panel having a pair of slots at each of two corners, a loop-forming strap at each of said corners and having its ends projected into said slots and secured between the layers 95 by the stitches thereof.

3. A card case comprising a pair of rectangular panels hingedly secured together, each of said panels comprising two layers of material stitched together, the inner layer of 100 each panel having a pair of slots at each of

two corners, a loop-forming strap at each of said corners and having its ends projected into said slots and secured between the layers by the stitches thereof, said slots being parallel with each other.

4. A card case comprising a pair of rectangular panels hingedly secured together, each of said panels comprising two layers of material stitched together, the inner layer of

each panel having a pair of slots at each of two corners, a loop-forming strap at each of said corners and having its ends projected into said slots and secured between the layers by the stitches thereof, said slots being parallel with each other, and parallel with one edge of the panel.

In testimony whereof I affix my signature.
JOSEPH M. HURLEY.
